OIL BURNING APPARATUS

Henry L. Ortlepp, Belleville, N. J., assignor to
Home Oil Heating Company, a corporation of
New Jersey

Application May 27, 1938, Serial No. 210,311

3 Claims. (Cl. 158—77)

This invention relates to oil burning apparatus of the type wherein oil is supplied to a rotatable head and through centrifugal force ejected through a series of nozzles with which the head is provided against an annular igniting plate or combustion rim located adjacent the walls of the boiler where the oil is ignited and burned. In burners of this type, the air to support combustion is usually supplied by a fan, which, in the particular embodiment herein disclosed, consists of a series of fan blades disposed at an angle with respect to the radii of the burner head and arranged vertically about the periphery thereof. According to this arrangement, the air is drawn up past the burner head and admixed with fuel as it is ejected from the nozzles, the air helping to atomize the fuel so that, when the latter reaches the combustion ring, it will be in condition for ready igniting.

The burner head and fan are both mounted on and for rotation by a power driven shaft and, since they are located in the combustion chamber of the boiler, it has been found that the heat conducted by the metal parts to the fuel ejecting tubes at the position where they are located in the head, is such as to effect carbonizing or coking of the oil at this point, resulting in flash backs or explosions in the head. The carbon deposits also tend to clog up the tubes, thereby preventing ejection of the oil and occasioning leakage of the latter into the pit below the boiler. This is often followed by pit fires, with consequent damage to the apparatus.

According to the present improvements, there is provided, in association with the burner head, a truncated baffle which directs the air in its passage to the combustion chamber, into close proximity to the burner head in the region where the ejecting tubes are connected thereto, thus materially increasing the velocity of the air at this point. It has been found that, when operating the burner at its usual or normal capacity and rate of speed, the increase in air velocity is such as to reduce the temperature of the head in the critical region mentioned below the point at which carbonization or coking of the fuel occurs.

Referring to the drawings:

Fig. 1 is a vertical cross sectional view through a boiler provided with a burner equipped with the present improvements;

Fig. 2 is a perspective view of the truncated baffle for deflecting the air against the burner head;

Fig. 3 is a plan view of the burner head, with

a portion of the fan cut away to show the baffle; and

Fig. 4 is a plan view of the burner, with the fan removed and with a portion of the baffle and burner head cut away to disclose the underlying parts.

Referring to Fig. 1, there is shown the lower portion of a boiler having water legs A and a hearth B defining the floor of the combustion chamber. Centrally located with respect to the hearth is an oil burner comprising a support C on which is mounted an electric motor D for driving the rotating parts. A rotatable shaft E driven by the motor extends vertically up through a bearing F likewise mounted in the support C and which is tapered at its upper end, as at E¹, to receive a rotatable head. The rotatable head includes a top member G¹ presenting a hub G² centrally drilled to fit the tapered portion of the shaft and presenting a depending flange G³ having a series of apertures to receive fuel ejecting tubes G⁴ extending radially outwardly from the head and which are usually four in number (see Figs. 1 and 3). Fastened at the periphery of the flange G³ is an annular member G⁵ having an inclined portion which extends downwardly and inwardly, and formed at its lower end with an upturned flange G⁶, providing an oil receiving trough or cup. The flange is spaced from the shaft E a distance sufficient to permit the passage of a tube H through which the oil is supplied to the cup. The tube H, at its upper end, terminates in a spout H¹ to permit the oil to drop evenly into the trough or cup and is mounted in a fixed member F¹ supported by the frame above the bearing F. The tube supporting member F¹ is formed at its periphery with a flange F² extending upwardly beyond the lower end of the rotatable cup, so that very little or no air will pass into the cup through the central opening.

The air to support combustion is introduced into the combustion chamber by means of a fan J which, as shown in Figs. 1 and 3, includes a closed top plate J¹ fastened at the top of the vertical shaft E by means of a nut, and which has a circular depending flange J² of a diameter somewhat larger than the distance between the outer ends of a pair of diametrically opposed ejecting tubes G⁴, and which is formed with a series of vertical fan blades J³ located at an angle with respect to the radii of the fan itself, and spaced evenly about the flange J², except in those portions opposite the tubes G⁴ where blades are omitted to allow the uninterrupted projection of oil therethrough (see Fig. 3). The fan, at its lower edge,

terminates above a circular stack K fixed on the support and against which the bricks of the hearth abut. Air is introduced from beneath the burner and passes upwardly through shutters L 5 formed in a truncated element L¹ (see Figs. 1 and 4), which rests on the support adjacent the lower edge of the stack and which terminates at the top substantially at the upper edge of the tube supporting member F¹.

10 During the operation of the arrangement just described, the burner head, which includes the oil receiving cup G⁵, the tubes G⁴ and the fan J, is rotated by the motor D; the oil, under the action of centrifugal force, climbs upwardly along the inclined surface of the cup G⁵ and into the tubes, whereupon it is ejected from the latter, and combined with a mixture of air drawn up by the fan. The oil, still in liquid form, although somewhat atomized by virtue of the air admixed 15 therewith, is thrown outwardly to an annular combustion ring M located adjacent the wall of the boiler. The oil is volatilized and ignited in the region of the combustion ring, and consequently burns in close proximity to the water leg 20 of the boiler, the heat of combustion being most effectively utilized in this way. The flame is evenly distributed by an annular grill M¹ extending around the boiler and supported by the combustion ring.

25 The mechanism, as thus far described, is old, and while it has met with substantial commercial success, it presents a serious difficulty, in that the heat from the combustion chamber is transmitted through the upper plate G¹ of the combustion head to the tubes G⁴ and, at the point where the latter are disposed in the combustion head, causes cracking of the oil and the formation of carbon deposits, thus tending to clog the tubes. This occasions flash backs or explosions in 30 the combustion head, and also occasional overflowing of the oil above the inner edge G⁶ of the cup and up over the edge of the flange F² on the tube supporting element F¹. The oil then drips down into the pit below the hearth, so that pit fires may and sometimes do occur.

35 In accordance with the present improvements, there is provided means for substantially increasing the velocity of the air as it flows past the portion of the head wherein the tubes are inserted without, however, increasing the total volume of air supplied by the burner to support combustion. As shown in Figs. 1 and 2, the means referred to includes a baffle N in the form of a truncated cone, the wall of which extends upwardly and inwardly from the upper edge of the stack K to a level substantially at the lower edge of the flange G³ presented at the periphery of the burner head top G¹. The truncated portion is flared at the top, as at N¹, and is supported 40 in position by a series of legs N² extending downwardly inside of the stack and resting upon the shutter member L¹ near the bottom of the latter. With this arrangement, the air, as it is drawn up through the shutters L, is deflected inwardly 45 by the baffle N and caused to impinge upon the burner head in the region where the tubes are inserted therein. In other words, the air has its greatest velocity as it passes the region where the trouble occurs, and consequently the greatest 50 cooling effect upon the burner. After passing through the constricted region, the air is permitted to travel toward the ends of the tubes

G⁴ without undue agitation by reason of the flared portion N¹.

According to a series of actual tests made, the temperature of the head was reduced from 670° F. without the improved baffle to 480° F. with the 5 baffle, these temperatures representing the average of the tests. The latter temperature of 480° F. is well below the temperature at which the oil used with these burners will crack and coke. The absence of coking obviates the disadvantages previously alluded to.

Another advantage flowing from the use of the baffle is an improvement in burner efficiency. Naturally, to the extent that the burner head is cooled, the air is correspondingly heated, and it 15 is well known that boiler efficiency can be improved by preheating the combustion air.

Still another advantage is a substantial decrease in cost of maintenance, this being adequately shown by a series of trial or test installations of the improved burner.

In the accompanying drawings, the invention has been shown merely by way of example and in preferred form, and obviously many variations and modifications may be made therein which 25 will still be comprised within its spirit. It is to be understood, therefore, that the invention is not limited to any specific form or embodiment, except insofar as such limitations are specified in the appended claims.

Having thus described my invention, what I claim is:

1. In a burner construction of the type including, in combination, a rotatable power driven vertical drive shaft, a burner head including a 35 plate element fixed on said shaft and having a diameter considerably larger than that of the shaft, a downwardly and inwardly sloping annular member mounted at its upper edge on said plate element near the periphery thereof and formed at its lower edge with an upwardly rebent portion providing a channel to receive liquid fuel, the lower edge of said member being spaced sufficiently from the shaft to provide for the passage of a pipe through which the liquid fuel is delivered to said channel, a plurality of fuel 40 ejecting nozzles extending outwardly from the periphery of said plate element, a fan arranged outside the nozzles and rotatable by the power driven shaft for drawing air to support combustion up past the head for admixture with the fuel, a stack arranged below the fan in spaced relation therewith and through which the air is drawn by said fan, said stack being also located below that portion of the plate element from 45 which the nozzles project, an imperforate baffle of generally truncated conical form extending from the top of the stack upwardly and inwardly to a position in close proximity to where the nozzles project from the plate element and acting 50 to increase the velocity of air flow at such position substantially above the velocity of air flow in the stack.

2. A burner construction according to claim 1, wherein the imperforate truncated baffle is formed 55 at its upper edge with a rebent outwardly extending flange.

3. A burner construction according to claim 1, wherein the imperforate truncated baffle is provided with means for mounting said baffle on the 60 stack.

HENRY L. ORTLEPP.
